HOT WATER OR STEAM BOILER

Elmer Jesse Lee, Bangor, Pa., assignor of one-third to Robert R. Schultz, Bangor, Pa.

Application July 23, 1940, Serial No. 347,004

1 Claim. (Cl. 122—225)

This invention relates to boiler construction, especially designed for hot water or steam heating plants, the primary object of the invention being to provide means to cause the water entering the boiler to be quickly heated, facilitating the rapid circulation of water or steam through the boiler and system associated therewith.

An important object of the invention is to provide a boiler of this character having means to retard the circulation of the incoming water at a point adjacent to the fire-box of the boiler, thereby rapidly heating the comparatively cool incoming water and preventing the mixing of the incoming water with the hot water of the boiler, until the incoming water reaches a predetermined temperature or a temperature which will not cool the water of the boiler to retard circulation thereof.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to drawings:

Figure 1 is a vertical sectional view through a boiler constructed in accordance with the invention, and taken on line 1—1 of Figure 2.

Figure 2 is a sectional view taken on line 2—2 of Figure 1.

Figure 3 is a transverse sectional view taken on line 3—3 of Figure 2.

Figure 4 is a sectional view taken on line 4—4 of Figure 1.

Figure 5 is a fragmental sectional view through a modified form of the invention.

Referring to the drawings in detail, the reference character 5 designates the outer wall of the boiler, and the reference character 6 designates the inner wall thereof, which is spaced from the outer wall, providing a compartment for the water to be heated in the boiler.

As shown, the inner wall of the boiler is provided with offset portions 7 extending around the entire inner wall.

The feed water pipes of the boiler are indicated by the reference character 8 and extend into the space between the outer wall 5 and inner wall 6 of the boiler, at a point adjacent to the bottom thereof, but in spaced relation therewith, as clearly shown by Figure 1 of the drawings.

5 Mounted within the boiler and disposed substantially intermediate the space between the outer and inner walls thereof, is a partitioning member 9 which completely encircles the main portion of the inner wall of the boiler, the lower end of the partitioning member 9 being spaced from the bottom 10 of the boiler. As clearly shown by Figure 1 of the drawings, the lower end of the partitioning member 9 is disposed above 10 the feed water pipes, so that water entering the space between the outer and inner walls of the boiler, will be directed inwardly against the inner wall 6, at a point adjacent to the fire-box 11 of the boiler, or at a point where the boiler is the hottest.

15 Formed integral with the partitioning member 9, are ribs 12 which are substantially wide and extend appreciable distances into the offset portions 7, the inner edges of the ribs being spaced from the inner wall, providing irregular passageways from the bottom to the top of the boiler. Due to this construction, it will be seen that incoming water will take the path as indicated by the arrows in Figures 1 and 2 of the drawings, 20 and circulate from the space between the inner surface of the partitioning member and inner wall 6 of the boiler, to the space between the outer surface of the partitioning member 9 and inner surface of the outer wall of the boiler, until 25 the temperature of the feed water has reached a predetermined degree to circulate and mix with the heated water held in the upper portion of the boiler. The water held within the boiler and which has been heated, is therefore maintained at 30 a high degree of temperature and is not cooled by the feed water which of course is cold, and which enters the boiler to replenish the supply. 35

40 In the form of the invention as shown by Figure 5 of the drawings, the outer wall of the boiler is indicated by the reference character 13 and the inner wall which is spaced from the outer wall is indicated by the reference character 14.

45 A partitioning member 15 is mounted within the space between the outer wall 13 and inner wall 14, dividing the space into passageways. The lower end of the partitioning member 15 is also spaced from the bottom of the boiler, and is arranged directly above the feed water pipe 16, which is shown as entering the boiler at a point adjacent to the fire-box 17, or at a point where the boiler is the hottest. Therefore the water entering the boiler will circulate over the upper end of the partitioning member and down through the space between the partitioning member 50 and outer wall 13, until the temperature of 55

the water has reached a predetermined degree, whereupon the feed water which has become heated, will circulate with the water held at the upper end of the boiler.

While I have shown and described a hot water or steam boiler of rectangular formation, it is to be understood that the principles of the invention may be effectively carried out in circular or round boilers, without departing from the spirit of the invention.

In view of the foregoing detail description, a further detail description as to the operation of the boiler is believed to be unnecessary.

What is claimed is:

A boiler of the class described, comprising spaced outer and inner walls, the inner wall hav-

ing inwardly extended offset portions providing vertically spaced horizontal grooves extending around the inner wall, vertical partitions mounted within the space between the outer and inner

- 5 walls and spaced from the outer and inner walls, wide ribs extending inwardly from the partitions and disposed in the grooves in spaced relation with the walls of the grooves, providing an inner irregular passageway, and an outer passageway,
- 10 a feed pipe adapted to direct water to the lower end of the passageways to flow upwardly through the irregular passageway and downwardly through the outer passageway, whereby the inflowing water is preheated on its upward passage
- 15 through the irregular passageway.

ELMER JESSE LEE.
